UNITED STATES PATENT OFFICE.

RICHARD R. PEARSON, OF SEYMOUR, CONNECTICUT.

MOP-WRINGER.

SPECIFICATION forming part of Letters Patent No. 739,504, dated September 22, 1903.

Application filed April 8, 1903. Serial No. 151,620. (No model.)

To all whom it may concern.

Be it known that I, RICHARD R. PEARSON, a citizen of the United States, residing at Seymour, county of New Haven, State of Connecticut, have invented a new and useful 5 Mop-Wringer, of which the following is a specification.

My invention relates to the class of mop-wringers adapted for attachment to pails.

10 It is one of the objects of the invention to provide a mop-wringer whose movable presser-board shall be free to oscillate in the vertical plane, so as to make it self-adjusting to the shape of the mop that is to be squeezed.

15 Further objects of the invention are to generally simplify and strengthen the construction of the device as a whole, so as to reduce the cost of construction to the minimum, to add greatly to the durability, and to improve 20 the mode of operation in general use.

With these and other objects in view the invention consists in certain constructions and in certain parts, improvements, and combinations, which will be hereinafter described 25 and then specifically pointed out in the claims hereunto appended.

In the accompanying drawings, forming part of this specification, in which like characters of reference indicate the same parts, 30 Figure 1 is an elevation of my novel mop-wringer with the lever connection in section; Fig. 2, a transverse section on the line 2 2 in Fig. 1, the device being represented in the operative position on a pail, which is indicated by 35 dotted lines, a squeezing position of the movable presser-board being also indicated by dotted lines; Fig. 3, a detail sectional view on the line 3 3 in Fig. 1, and Fig. 4 is a plan view illustrating the oscillatory movement of 40 the movable presser-board.

10 denotes the stationary presser-board, 11 side pieces, and 12 a bottom piece, all of which are rigidly secured together.

13 denotes the movable presser-board, on 45 the outer face of which is a metallic cross-piece 14, terminating in a downwardly-extending curved arm 15, whose engaging tip 16 is turned at an angle and engages an eye 17 upon an eyepiece 18, which is rigidly secured

to a leg 19, itself rigidly secured to the outer 50 side of the stationary presser-board and adapted to engage the inner side of a pail in use, as clearly indicated in Fig. 2. The eyepiece serves also as a retaining-clamp for a spring 20, one arm of which bears against the 55 inner side of arm 15 and acts to throw the movable presser-board to the retracted position, as in full lines in Fig. 2. The movable presser-board is operated by means of a toggle 60 consisting of arms 21, extending from a rock-shaft 22, which is journaled in the side pieces outside of the movable presser-board, and an arm 23, which is hinged to the outer end of arms 21 and is provided with a rounded head 24, which engages a socket 25 in the 65 outer face of cross-piece 14. The rock-shaft is oscillated by means of a lever 26, which is rigidly secured thereto in any ordinary or preferred manner—for example, as indicated in Fig. 1. Upon the inner faces of the side 70 pieces are bearing-plates 27, through which the ends of the shaft pass, said plates being provided with downwardly-extending holding-lugs 28, which pass on the outer side of a pail in use, and with stops 29, which limit the 75 backward movement of the movable presser-board, and one of said plates being provided with a stop 30, the respective ends of which are adapted to be engaged by a double lug 31 on the rock-shaft to limit the oscillation 80 of the rock-shaft in either direction. The rear ends of the side pieces are cut away, so as to form rests 32, (see Fig. 3, one rest only appearing,) which engage the top of a pail in use, and below the rests the side pieces 85 are inclined and beveled, as at 33, to adapt that portion of the side pieces to pass within a pail.

In use the wringer is set over the edge of the pail, as indicated in Fig. 2, in which the 90 pail appears in dotted lines. Rests 32 on the side pieces engage the top of the pail, leg 19 engages the inner side of the pail, and holding-lugs 28 the outer side of the pail, so that there is no danger of the ringer becoming detached from the pail in use. Spring 20 is 95 strong enough to always retain the parts in the position shown in full lines in Fig. 2.

- The use is the same as other devices of this character. The mop is placed between the presser-boards and the movable presser-board moved inward toward the stationary 5 presser-board by movement of the lever toward the right from the position shown in Fig. 2. This oscillates the rock-shaft, straightens the toggle, and forces the movable presser-board toward the position shown in dotted 10 lines, thereby squeezing the mop. The important difference between my improved mop-wringer and others of its class is the self-adjustability of the movable presser-board, as illustrated in Fig. 4, whereby it adapts itself 15 to the thickness of a mop. For example, where the ends of the presser-board must move uniformly—that is, each must move the same distance, as in all former constructions of which I am aware—if the mop is not of uniform thickness the thick side will be squeezed, but no pressure whatever will be brought to bear upon the thin side. In my improved 20 mop-wringer, however, the movable presser-board may oscillate freely in the vertical 25 plane, owing to the fact that the engagement of the tip of arm 15, which carries the movable presser-board with eye 17, is a loose engagement and the engagement of rounded head 24 with the socket in cross-piece 14 is 30 also a loose engagement. The movable presser-board as it is moved forward is free to adjust itself to the thick and thin sides of a mop, so that the thin side of a mop will be squeezed as well as the thick side. As soon as pressure 35 upon the lever is relieved the spring, through its engagement with arm 15, will return the movable presser-board and lever to the position shown in full lines in Fig. 2, the return movement continuing until the presser-board 40 engages the stops 29 upon the bearing-plates. Simultaneously, also, one end of lug 31 upon the rock-shaft will engage one end of stop 30, so as to hold the rock-shaft against further oscillation in that direction. The oscillation 45 of the rock-shaft in the opposite direction is limited by the engagement of the other end of double lug 31 with the other end of stop 30.
- Having thus described my invention, I claim—
- 50 1. A mop-wringer comprising a stationary presser-board and side and bottom pieces, a movable presser-board carried by a central arm and means for moving said movable presser-board inward, universal joints being provided at the lower end of said central arm and at the connection between the movable board and the means for moving it, whereby said movable board is self-adjusting in the vertical plane.
- 55 2. A mop-wringer comprising a stationary presser-board and side and bottom pieces rigidly secured thereto, a movable presser-board adapted to swing over the bottom piece, an arm by which the movable presser-board is

carried, a single centrally-located fixed leg 65 depending from the stationary presser-board and adapted to engage the inner side of a pail to which said arm is pivotally connected by a universal joint and means for actuating the movable presser-board, the said movable 70 board being loosely connected with the means for actuating it whereby it will be self-adjusting in the vertical plane.

3. A mop-wringer comprising a stationary presser-board and side and bottom pieces rigidly secured thereto, a movable presser-board adapted to swing over the bottom piece, an arm by which the movable presser-board is carried and which is pivotally connected by a universal joint to a fixed portion of the device, means for swinging the movable presser-board inward, the said movable board being loosely connected with the means for actuating it whereby it will be self-adjusting in the vertical plane and a spring engaging the arm 85 for returning the movable presser-board to its normal position when pressure is relieved.

4. A mop-wringer comprising a stationary presser-board and side and bottom pieces rigidly secured thereto, bearing-plates upon the 90 side pieces having stops 29, a movable presser-board self-adjusting in the vertical plane, a rock-shaft journaled in the side pieces and the bearing-plates and a toggle intermediate the rock-shaft and the presser-board whereby 95 the latter is actuated through oscillation of the rock-shaft, the return movement of the presser-board being determined by engagement with stops 29.

5. A mop-wringer comprising a stationary 100 presser-board and side and bottom pieces rigidly secured thereto, bearing-plates upon the side pieces one of which is provided with a stop 30, a movable presser-board self-adjusting in the vertical plane, a rock-shaft journaled in the side pieces and the bearing-plates and having a double lug adapted to engage the ends of stop 30 to limit oscillation in either direction, and a toggle intermediate 105 the rock-shaft and the presser-board, substantially as shown, for the purpose specified.

6. A mop-wringer comprising a stationary presser-board and side and bottom pieces rigidly secured thereto, said side pieces having rests 32, bearing-plates upon the side pieces 115 having holding-lugs 28, a leg 19 rigidly secured to the stationary presser-board and adapted to engage a pail, a movable presser-board, an arm by which it is carried and which is pivotally connected to the leg, a rock-shaft and a toggle intermediate the rock-shaft and the movable presser-board, whereby 120 the latter is operated.

7. A mop-wringer comprising a stationary presser-board and side and bottom pieces rigidly secured thereto, a movable presser-board, a cross-piece on the outer side thereof having a socket 25 and a downwardly-extending

arm having an engaging tip, a leg rigidly secured to the stationary presser-board, an eye-piece rigidly secured to the leg and having an eye which is engaged by the tip of the

whereby the movable presser-board is retained at its normal position. 10

In testimony whereof I affix my signature in presence of two witnesses.
